US00D897864S

(12) **United States Design Patent** (10) **Patent No.:** **US D897,864 S**
(45) **Date of Patent:** **** Oct. 6, 2020**

(54) **PACKAGING CASE**

(71) Applicant: **Dae Seob So**, Daejeon (KR)

(72) Inventor: **Dae Seob So**, Daejeon (KR)

(**) Term: **15 Years**

(21) Appl. No.: **29/628,487**

(22) Filed: **Dec. 5, 2017**

(30) **Foreign Application Priority Data**

Jun. 7, 2017 (KR) 30-2017-0025673

(51) **LOC (12) Cl.** **09-03**

(52) **U.S. Cl.**

USPC **D9/737; D9/426**

(58) **Field of Classification Search**

USPC D9/341, 347, 414-432, 440, 444, 447, D9/449-454, 503, 504, 737, 759, 761, D9/456; D7/672, 601, 550.1, 551.1, D7/551.2, 551.3, 552.1, 552.2, 553.1, D7/553.2, 553.4, 553.5, 553.7, 553.8, D7/554.1, 554.3, 555, 557, 602, 629, 630, D7/538-542, 612-615, 584, 586, 587, D7/392.1, 709, 502, 608, 622, 701, 703, D7/543-549, 317-319, 391, 392, 396.2, D7/510, 511; D3/273, 201-206, 276, D3/283, 284, 295, 274, 302, 901; 220/575, 500, 505-507, 523, 553, 555, 220/556; 206/216, 217, 541-550, 518, 206/557, 558, 561, 562, 564, 223, 467; 229/107, 406, 120, 125.17; 249/126, 249/134; 426/106; 215/211, 200, 224, 215/243; D28/56, 61, 73

(57) **CLAIM**

The ornamental design for a packaging case, as shown and described.

DESCRIPTION

FIG. 1 is a perspective view of a packaging case showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a reference view thereof for showing a state of disassembly.

1 Claim, 7 Drawing Sheets
